(57) **CLAIM**

The ornamental design for an electronic device with retractable leg support, as shown and described.

DESCRIPTION

FIG. 1 is a perspective view illustrating a design for an electronic device with retractable leg support in a retracted position according to one embodiment;

FIG. 2 is a bottom view thereof;

FIG. 3 is a top view thereof;

FIG. 4 is a side view thereof;

FIG. 5 is another side view thereof;

FIG. 6 is a back view thereof;

FIG. 7 is a front view thereof;

FIG. 8 is a perspective view illustrating a design for an electronic device with retractable leg support in an extended position according to one embodiment;

FIG. 9 is a front view thereof;

FIG. 10 is a back view thereof;

FIG. 11 is a side view thereof;

FIG. 12 is another side view thereof;

FIG. 13 is a bottom perspective view thereof; and,

FIG. 14 is a top perspective view thereof.

The broken lines of the FIGURES are for illustration only. The broken lines and the unshaded regions bounded by broken lines of the preceding FIGURES illustrate boundaries and, therefore, form no part of the claimed design. Non-oblique line shading is meant to show contour and not surface ornamentation. Additionally, it should be noted that any of the corners of any of the embodiments shown may be rounded or squared off at various angles based on a particular embodiment.
